Primary Examiner — Lauren R Calve*(74) Attorney, Agent, or Firm* — Stites & Harbison PLLC; Richard S. Myers, Jr.(57) **CLAIM**

The ornamental design for a tiered hanger, as shown and described.

DESCRIPTION

FIG. 1 is a front perspective view of a tiered hanger of the present invention;

FIG. 2 is a front elevation view of the tiered hanger shown in FIG. 1;

FIG. 3 is a left side elevation view of the tiered hanger shown in FIG. 1;

FIG. 4 is a right side elevation view of the tiered hanger shown in FIG. 1;

FIG. 5 is a top plan view of the tiered hanger shown in FIG. 1;

FIG. 6 is a bottom plan view of the tiered hanger shown in FIG. 1; and,

FIG. 7 is a rear elevation view of the tiered hanger shown in FIG. 1.

The broken lines shown represent elements of the claim that form no part of the claimed design.

1 Claim, 5 Drawing Sheets(56)
